US0D1073564S

(12) **United States Design Patent** (10) **Patent No.:** **US D1,073,564 S**
(45) **Date of Patent:** **** May 6, 2025**

(54) **VEHICLE REAR CLAMSHELL**

(71) Applicant: **Dr. Ing. h.c. F. Porsche
Aktiengesellschaft**, Stuttgart (DE)

(72) Inventors: **Shuichi Yamashita**, Stuttgart (DE);
Woosung Chung, Stuttgart (DE)

(73) Assignee: **Dr. Ing. h.c. F. Porsche
Aktiengesellschaft** (DE)

(**) Term: **15 Years**

(21) Appl. No.: **29/914,682**

(22) Filed: **Oct. 20, 2023**

(30) **Foreign Application Priority Data**

Jun. 5, 2023 (EM) 015023618-0012

(57) **CLAIM**

The ornamental design for a vehicle rear clamshell as shown and described.

DESCRIPTION

FIG. 1 is a perspective view of a vehicle rear clamshell showing our design;

FIG. 2 is a front view thereof;

FIG. 3 is a rear view thereof;

FIG. 4 is a right view thereof;

FIG. 5 is a left view thereof;

FIG. 6 is a top view thereof; and,

FIG. 7 is a bottom view thereof.

The broken lines in the drawings surround portions of the vehicle rear clamshell that form no part of the claimed design.

1 Claim, 7 Drawing Sheets
